UNITED STATES PATENT OFFICE.

CHARLES D. HASKINS, OF NEW YORK, N. Y., ASSIGNOR TO THE UNION ELECTRIC MANUFACTURING COMPANY, OF SAME PLACE.

ELECTRIC GAS-LIGHTER.

SPECIFICATION forming part of Letters Patent No. 251,777, dated January 3, 1882.

Application filed May 31, 1881. (No model.)

To all whom it may concern:

Be it known that I, CHARLES D. HASKINS, of the city, county, and State of New York, have discovered certain new and useful Improvements in Electric Gas-Lighters, of which the following is a full, clear, concise, and exact description, reference being had to the accompanying drawings, forming part of this specification.

10 My invention relates to that class of electric gas-lighters in which the electric spark is formed just after the valve in the burner is opened, so that the gas as it begins to escape will be ignited by the spark. The spark is formed by breaking contact between the points of two wires or electrodes near the tip.

15 Prior to my invention the pawl and ratchet were kept in position by means of a pawl-spring.

20 My invention consists in pivoting the pawl directly to the arm and adjusting the pendant to the outer side of the pawl, so that the weight of the pawl and pendant will hold the pawl in engagement with the ratchet-wheel, and in the 25 specific mechanism hereinafter more particularly described and shown.

In the drawings, Figure 1 is a side elevation of a pendent electric gas-lighter embodying my improvements. Fig. 2 is a rear view 30 thereof, in which certain parts are shown in section.

35 *a* is the pillar, which is of the ordinary form. *b* is the ratchet-wheel and valve. Openings *c* are provided in the valve, so that the gas may be turned on and off alternately as the pendant is pulled down.

40 *d* is the contact-lever, provided with three lugs, to one of which the pawl *e* is pivoted, the other two lugs serving to limit the motion of the contact-lever as they are brought against the stop, so attached to the pillar as to come between them.

45 *f* is the pendant, attached to the eyelet provided upon the outer portion of the pawl and below the point where the pawl is pivoted with the contact-arm.

50 *g* is a metallic ring, insulated by asbestos paper *h*.

i is the contact-point attached to the insulated ring, and *k* is the contact-point which is carried by the contact-arm.

l is a coil-spring, which holds the contact-lever *d* normally in the position shown. The battery is so connected that when the points *i k* are in contact the circuit is closed, and on breaking the contact between these two points the circuit is opened. The contact-lever and valve are operated when the pendant is pulled down. The contact-points are thus brought together, and the circuit held closed until the wire *k* slips by wire *i*, and then the contact is broken, and the spark formed just as the gas, which has been turned on by the opening of the valve, begins to escape. The spring *l* carries the contact-lever back to its normal position when the pendant is released, and thus a second contact is made and broken. This produces a second spark, which is of advantage in case the first spark should not ignite the gas. The next time the pendant is pulled down the gas is turned off and the light extinguished. Thus the gas is lighted and extinguished simply by pulling down the pendant.

55 My electric gas-lighter as thus described contains fewer parts and less complicated mechanism than any heretofore used that I have seen, while its operation is more simple and satisfactory than that of those containing more complicated mechanism.

70 I claim—

75 1. In an electric gas-lighter, the combination of the pawl *e*, pivoted to the contact-lever *d*, with pendant *f*, attached to the outer portion of said pawl, whereby the weight of said pawl and pendant hold the pawl in engagement with the ratchet, substantially as shown and described.

80 2. The combination, in an electric gas-lighter, of pillar *a*, ratchet and valve *b*, provided with openings *c*, contact-arm *d*, provided with three lugs, pawl *e*, pivoted to one of the lugs, pendant *f*, attached to the outer portion of the pawl and below the pivotal point, contact-points *i k*, spring *l*, and the stop attached to the pillar, substantially as and for the purpose specified.

85 CHAS. D. HASKINS.
